UNITED STATES PATENT OFFICE.

THOMAS G. BENNETT, OF NEW HAVEN, CONNECTICUT, ASSIGNOR TO
WINCHESTER REPEATING ARMS CO., OF NEW HAVEN, CONNECTICUT,
A CORPORATION.

FIREARM.

No. 836,554.

Specification of Letters Patent.

Patented Nov. 20, 1906.

Application filed February 19, 1906. Serial No. 301,839.

To all whom it may concern:

Be it known that I, THOMAS G. BENNETT, a citizen of the United States, residing at New Haven, in the county of New Haven and State of Connecticut, have invented a new and useful Improvement in Firearms; and I do hereby declare the following, when taken in connection with the accompanying drawings and the characters of reference marked thereon, to be a full, clear, and exact description of the same, and which said drawings constitute part of this specification, and represent, in—

Figure 1, a broken view in right-hand side elevation of a gun constructed in accordance with my invention, with its sliding fore-arm in its rearward position, which under my invention it occupies when the gun is ready for firing and which therefore becomes its normal position; Fig. 2, a broken view of the gun, partly in elevation and partly in vertical section, with the fore-arm in its forward position, into which it is moved preparatory to its use for moving the breech-block rearward, and so opening the gun; Fig. 3, a view of the gun in front elevation, with particular reference to showing the fore-arm tip; Fig. 4, a view of the gun in vertical section on the line *a b* of Fig. 1; Fig. 5, a detached view in side elevation of the balanced breech-block; Fig. 6, a view thereof in front elevation; Fig. 7, a detached view in side elevation of the sliding fore-arm; Fig. 8, a view thereof in front elevation; Fig. 9, a detached view in side elevation of the fore-arm tip; Fig. 10, a view thereof in front elevation; Fig. 11, a detached view of the washer-like lever-operating cam; Fig. 12, a view thereof in front elevation; Fig. 13, a plan view of the operating-lever; Fig. 14, a view thereof in side elevation.

My invention relates to an improvement in that class of guns having what are known as "balanced" breech-blocks, as distinguished from breech-closures positively held in their closed positions, so as to take the thrust of recoil. Balanced breech-blocks as heretofore constructed have been employed in automatic guns and made so as to move back under the thrust of recoil and in moving back operate the breech mechanism of the gun, a balance being established between the thrust of recoil and the inertia of the mass of the block and the power of the block-closing spring and the power required to open the

breech mechanism. In the gun of my present improvement the breech-block is balanced in the sense that it is not positively held in any way to take the thrust of recoil, but so adjusted in weight and in the power of its spring to the thrust of recoil as to remain at rest in its closed position at the time the gun is fired.

The object of my invention is to produce a simple, effective, and durable manually-operable balanced breech-block gun constructed with particular reference to having the breech-block remain at rest when the gun is fired and to avoiding that naked and unsightly appearance which proceeds from having the sliding fore-arm moved forward away from the receiver when the gun is closed and ready for being fired, as well as to constructing the sliding fore-arm so as to have the appearance of an ordinary fixed fore-arm.

With these ends in view my invention consists in a gun having certain details of construction and combinations of parts, as will be hereinafter described, and pointed out in the claims.

In carrying out my invention as herein shown I employ a breech-block 2, having a long forward extension 3, made heavy enough in its entire mass, when reinforced by its closing-spring 4, to remain at rest when the gun is fired. To accomplish this result, the block must be made heavier than balanced breech-blocks are generally made or have a closing-spring of superior power. For the reception of the spring 4 the extension 3 of the block is formed with a concentric spring-chamber 5, entered through an opening 6. The forward end of the said spring abuts against a shoulder 7 at the forward end of the said chamber 5, while its rear end abuts against the front face 8 of the gun frame or receiver 9.

As herein shown the gun is furnished with a tubular magazine 10, having its forward end supported by the gun-barrel 11 in any of the well-known ways and having its rear end inserted into a socket 12, formed in the receiver 9, the rear end of this magazine being encircled by the spring 4, for which it forms a guide. The said magazine extends through the fore-arm tip 13, the sliding fore-arm 14, and the breech-block extension 3, its rear end opening through the breech-block 2 into the inside of the receiver 9 through a feed-

opening 15, formed therein. The cartridges when fed out of the opening 15 may be lifted into position to be loaded into the gun-barrel 11 by an ordinary pivotal cartridge-carrier or 5 by any other suitable means. This mechanism forms no part of my present invention and is not shown or described. The fore-arm 14, which is suspended, as it were, on the magazine on which it slides back and forth, 10 is normally retracted or held at the limit of its rearward position with its rear end abutted against the front face of the receiver 9, to the cross-sectional form of which it corresponds in cross-sectional form. In other words, the 15 sliding fore-arm 14 though functioning as a sliding handle has in reality the form and appearance of an ordinary fixed fore-arm. The said fore-arm coacts with the breech-block for manually opening the same after every 20 time the gun is fired through an operating-lever 16, hung on a pivot 17, passing through its forward upper corner and mounted in the fore-arm tip 13, which is secured within the forward end of the fore-arm by means of two 25 transversely-arranged screws 18 18 or in any other equivalent way. The heel 19 of the said lever 16 is engaged by a spring-plunger 20, mounted in the fore-arm tip 13 and exerting a constant effort to lift the cam-like rear 30 end of the lever upward into its operating position, in which it enters a coupling-notch 21 in the forward lower corner of the extension 3 of the breech-block. For the operation of the lever 16 I fix a washer-like cam 22, having a bearing-sleeve 23, upon the magazine 10 in such position that when the fore-arm is retracted the lower edge of the cam is entered into a locking-notch 24 in the upper edge of the lever 16, whereby the fore-arm is held in 35 its retracted position.

When it is desired to open the gun, the fore-arm is grasped and pushed forward to cause the cam 22 to force the lever downward against the action of the spring-plunger 20 45 and ride out of the locking-notch 24, when the said plunger at once reasserts itself and swings the lever 16 so as to lift its rear end into position to snap into the coupling-notch 21 in the extension 3 as soon as the continued 50 forward movement of the fore-arm has brought the notch into registration with the rear end of the lever. Now when the fore-arm is drawn back with the lever so engaged with the breech-block extension the breech-block 2 will be forced back into its open position against the tension of its spring 4, which will be compressed. Just before the fore-arm reaches the limit of its rearward movement the beveled rear wall 25 of the locking- 55 notch 24 will engage with the front face of the cam 22 and the lever will be forced downward out of the coupling-notch 21, thus disconnecting the fore-arm from the breech-block and leaving the spring 4 free to assert 60 itself to draw the block 2 forward into its

closed position, in which the said spring holds it, the movement of the block in going into its closed position being relied upon to push the fed and lifted cartridge forward into the gun-barrel. When the fore-arm 14 completes its rearward movement, the cam 22 70 snaps into the locking-notch 24, whereby the fore-arm is held in its retracted position.

I particularly wish to emphasize the point that under my improved construction when 75 the gun is ready for firing the fore-arm is retracted, giving the gun the external appearance of a gun with a fixed fore-arm.

I claim—

1. In a firearm, the combination with the 80 receiver and the barrel thereof, of a breech-block balanced to remain in its closed position when the gun is fired, a breech-block-closing spring, a sliding fore-arm normally located at the limit of its rearward excursion, 85 and means carried thereby for operably connecting the fore-arm with the breech-block when the fore-arm is moved to the limit of its forward excursion.

2. In a gun, the combination with the receiver and the barrel thereof, of a breech-block balanced to remain in its closed position when the gun is fired, a breech-block-closing spring, a sliding fore-arm normally located at the limit of its rearward excursion, 95 and an operating-lever mounted in the fore-arm and operably connected with the breech-block when the fore-arm reaches the limit of its forward excursion, whereby the block is opened during the rearward excursion of the 100 fore-arm.

3. In a firearm, the combination with the receiver and barrel thereof, of a breech-block balanced to remain in its closed position when the gun is fired, a breech-block-closing 105 spring, a sliding fore-arm normally located at the limit of its rearward excursion, and an operating-lever pivoted at its forward end in the fore-arm and having its rear end adapted to be operably connected with the breech-block when the fore-arm reaches the limit of its forward excursion, whereby when the fore-arm is moved back the breech-block will be opened.

4. In a firearm, the combination with the 115 barrel thereof, of a breech-block balanced to remain in its closed position when the gun is fired, a breech-block-closing spring, a sliding fore-arm, and means to yieldingly hold the fore-arm at the limit of its rearward movement and for connecting it with the breech-block at the limit of its forward movement, whereby the fore-arm is moved into its forward position preparatory to its use for manually opening the gun after every time the 120 gun is fired to open the same.

5. In a firearm, the combination with the barrel thereof, of a breech-block having a forward extension and balanced to remain in its closed position when the gun is fired, a tu- 130

bular magazine on which the said forward extension slides, a breech-block-closing spring, a fore-arm sliding on the said magazine and normally located at the limit of its rearward excursion, and an operating-lever pivotally connected at its forward end to the said fore-arm and adapted to be operably connected with the forward extension of the balanced breech-block when the fore-arm is at the limit of its forward excursion.

6. In a firearm, the combination with the receiver thereof, of a breech-block, a spring therefor, a normally retracted sliding fore-arm conforming in cross-sectional form to the cross-sectional form of the receiver against

the front end of which its rear end is normally abutted, and means interposed between the fore-arm and breech-block, whereby when the fore-arm is moved forward it is coupled with the breech-block for manually moving the same rearward against the tension of the spring and thus opening the gun.

In testimony whereof I have signed this specification in the presence of two subscribing witnesses.

THOMAS G. BENNETT.
